UNITED STATES PATENT OFFICE.

JOHN MARTIN, OF KNIGHT'S FERRY, CALIFORNIA.

CAR-COUPING.

SPECIFICATION forming part of Letters Patent No. 293,899, dated February 19, 1884.

Application filed November 12, 1883. (No model.)

To all whom it may concern:

Be it known that I, JOHN MARTIN, of Knight's Ferry, county of Stanislaus, and State of California, have invented an Improvement in Car-Couplings; and I hereby declare the following to be a full, clear, and exact description thereof.

My invention relates to a new and useful car-coupling of that class in which swinging latches 10 on each draw-head are adapted to fall into engagement with the ends or heads of the coupling-pin.

My invention consists in a peculiarly-constructed draw-head chamber in a staple secured 15 to the under side of the gravitating-latch, adapted to receive and throw out the coupling-pin when necessary, and in the means for raising the latches from above or on the side to uncouple the cars, all of which I shall 20 hereinafter fully explain, reference being made to the accompanying drawings.

Figure 1 is a perspective view of my draw-head applied to a car, and the means for raising the latch. Fig. 2 is a vertical longitudinal 25 section of the draw-head, showing pin in position. Fig. 3 is a top view of the draw-head, showing the latch raised to show staple E. Fig. 4 is a side elevation of the draw-head, a portion being broken away to show the coupling-pin in position, its head in engagement 30 with the shoulder b', and its point in staple E.

The object of my invention is to provide a simple and effective automatic car-coupling, which shall be able to readily uncouple itself 35 in case of accident, or be easily uncoupled by design.

A is the end of a car, and B is a draw-head connected therewith in suitable manner.

C is the latch, which forms also the top of 40 the draw-head and completes the draw-head chamber b, which is formed in the under surface of the latch and the upper surface of the body of the draw-head. This chamber is formed with the usual flaring entrance, and 45 has an encircling shoulder b', behind which the enlarged conical head d of the coupling-pin D fits. The latch C is hinged to the draw-head, and is adapted by its own weight to fall down upon it. The pin D entering the draw-head forces up the latch sufficiently to allow 50 it to pass under until its head fits behind the

shoulder b', when the latch drops down and the pin is coupled and held behind the shoulder b'.

Secured to the under surface of the latch C 55 is a staple E, forming a socket. This staple, when the latch is down, projects downwardly into the draw-head chamber, into a cross-groove, e, made therein. In this position the head of the coupling-pin, entering the draw-head, extends a short distance into said staple. Now, when the latch is raised the staple lifts up the end or point of the head of the pin, carrying said head out of engagement with the shoulder b' and thus uncoupling it. This 65 operation would result in case of an accident which would tend to raise the latch—such as a derailment, where the relative position of adjoining cars would be changed. The raising of the latch would throw the coupling-pin 70 out, and thus by uncoupling the cars would prevent one dragging another off the track; but it is obvious that this ready adaptability to uncouple may be utilized by design, as when the brakeman wishes to uncouple the 75 cars. I have therefore shown means by which the latch may be raised to accomplish this result, both from the top and side.

Pivoted to the sides of the latch are arms F, the lower ends of which are pivoted to levers 80 G, having their forward ends pivoted to the sides of the draw-head near the front.

H is a frame or bail, the sides of which pass down on each side of the rear end of the draw-head. Upon these sides are loosely fitted the 85 rear ends of levers G, being prevented from falling off by heads h on the lower ends of the sides of the bail.

To the top of the bail is secured a rod, I, passing up through a guide-staple, J, in the 90 end of the car near its top. This rod is provided with a hand-loop, i, on top, and a catch, i', farther down. By raising this rod the bail H is raised, lifting the levers G and the arms F, which lift the latch C, to uncouple the device. The catch i' of the rod I, engaging with the staple J, holds the rod up and keeps the latch raised, when desired. It will be observed that though the elevation of the rod I raises the latch the movement of the latter 95 does not affect the former, because the rear ends of levers G simply play up and down.

loosely on the sides of the bail. Therefore the entrance of the coupling-pin under the latch and raising it slightly does not affect the bail or rod at all.

5 In order to uncouple from the side of the car, I have a long lever, K, fulcrumed at k, and pivoted on the rod I.

In the bottom of the draw-head chamber I make a hole, m, to permit the escape or discharge of sand, dust, grit, and other foreign material.

The other part of the device—namely, the opposite draw-head—is a duplicate of the part described, and the coupling-pin is alike at 15 both ends; but if a car provided with my coupling should have to be used with a car having the old style upon it, I could make a pin with a conical head at one end and a link or slotted head at the other.

20 Having thus described my invention, what I claim as new, and desire to secure by Letters Patent, is—

1. In a car-coupling, the draw-head B, hinged latch C, between which and said draw-head a chamber, b, having a front shoulder, b', is formed, for the reception and engagement of a coupling-pin, as described, in combination with the means for raising the latch, consisting of the pivoted arms F, levers G, bail H, 25 and rod I, substantially as herein described.

2. In a car-coupling, the draw-head B,

hinged latch C, between which and said draw-head a chamber, b, having a shoulder, b', is formed for the reception and engagement of a coupling-pin, D, and the staple E in the latch, 35 for the reception of the point of the pin, in combination with the means for raising said latch and staple to free the pin, consisting of the pivoted arms F, levers G, bail H, and rod I, substantially as herein described. 40

3. In a car-coupling, the draw-head B and hinged latch C, for receiving and engaging the coupling-pin, in combination with the arms F on the latch, the levers G on the draw-head, the bail H, upon the sides of which the rear 45 ends of lever G loosely play, and the rod I, substantially as and for the purpose herein described.

4. In a car-coupling, the draw-head B and swinging latch C, forming a chamber, with a shoulder for the reception and engagement of the coupling-pin D and the staple E in the latch, in combination with the means for raising said latch from the side of the car, consisting of the arms F, levers G, bail H, rod I, and lever K, 50 substantially as herein described.

In witness whereof I have hereunto set my hand.

JOHN MARTIN.
